COLD CATHODE GAS DISCHARGE TUBE

Leo R. Landrey, Lynbrook, N. Y., assignor to
Sylvania Electric Products Inc., a corporation
of Massachusetts

Application August 19, 1948, Serial No. 45,067

8 Claims. (Cl. 313—54)

1

The present invention relates to gas filled discharge devices, and more particularly to gas discharge tubes having a cold cathode.

An object of the present invention is the provision of a cold cathode gas filled discharge tube, having substantially no variation in firing characteristics between successive tests.

Another object of the present invention is the provision of a gas discharge tube having a high degree of stability.

A further object of the present invention is the provision of a cold cathode gas filled discharge tube having a more uniform field distribution between the electrodes whereby a more predictable discharge characteristic is obtained.

Still another object of the present invention is the provision of means within a gas discharge tube for assisting the initiation of the electric discharge within the tube, and for decreasing ionization time.

Still another object of the present invention is the improvement of the electrical characteristics of a cold cathode gas discharge device.

The foregoing objects, and others which may appear from the following detailed description are obtained by providing within a gas filled envelope a rod-like cathode, a semi-cylindrical anode having its convex surface facing the cathode, and an ionization producing strip of metal near the discharge region within the tube but still not directly in the discharge region.

In a preferred form of the present invention the semi-cylindrical anode is provided with an aperture therein at a point intermediate its ends. A getter capsule is secured to the anode on the concave side thereof with the discharge aperture of the capsule in line with the aperture in the anode. Thus, as the getter is flashed during the processing of the tube, the active material from within the getter capsule is sprayed through the aperture in the anode to strike the cathode rod, and thereby activate the rod. Some of the getter material, which does not strike the cathode rod, is deposited on the interior wall of the envelope and serves as a clean-up material for undesired gases within the tube.

The present invention is particularly directed to a further improvement of a gas discharge tube of the type disclosed in an earlier filed application by Gerald C. Rich, Serial No. 39,391 filed July 19, 1948, titled Cold Cathode Gas-Filled Diode, and assigned to the assignee of the present application.

The present invention will be more clearly understood by reference to the following detailed description, which is accompanied by a drawing in which

2

Fig. 1 illustrates in an enlarged elevational view, an embodiment of the present invention, while

Fig. 2 illustrates a transverse cross sectional view taken along line 2—2 of Fig. 1.

The gas discharge tube shown in Fig. 1 includes a sealed envelope 10, preferably of a vitreous material, filled with ionizable gas at a reduced pressure. Various gases may be used, 10 argon and/or neon being typical examples of gases which may be used. The discharge structure within the envelope includes a rod-like cathode 12 and an apertured semi-cylindrical anode 14. The semi-cylindrical anode 14 is provided 15 with wings 16 and 18 along the opposite vertical edges. To the wings 16 and 18 are attached support rods 20 which pass through insulating spacers 22 and 24, and serve to support the anode 14 and maintain it in its desired position within 20 glass envelope 10. The cathode 12 is a solid rod, which passes through apertures in the insulating spacers 22 and 24 to hold it in its proper position within the glass envelope 10, and in the proper spatial relationship with anode 14. 25 The support rods 20, and the cathode 12 are provided with conductive extensions passing through the header 26 at the base of the tube to form lead in wires 28. Anode 14 is provided at substantially its mid-point with an aperture 15. Aperture 15 may be provided by dividing anode 14 into two parts spaced apart at the center. Immediately in back of aperture or gap 15, between the two parts of the anode, and secured to the support rods 20 by means of a getter 30 supporting plate 17 is a getter capsule 17'. Alternatively, it may be secured directly to the concave surface of anode 14. The getter capsule is in the form of a hollow iron sleeve filled with a getter material such as barium or other alkaline earth metal. The capsule 17' is provided with a small aperture 19 on the side facing anode 14, that is, away from the supporting plate 17, and directly in line with the aperture in anode 14.

45 At one stage of the processing of the tube, plate 17 is heated by means of induction coils. Heat developed in plate 17, going to the getter capsule 17', causes the alkaline earth metal within the capsule to be vaporized and to spray out of aperture 19. Some of the vaporized material 50 is deposited on cathode rod 12 where it thereafter serves as an activating material for the cathode. Another portion of the vaporized metal is deposited on the inner wall of glass envelope 10 where it serves in a known manner to clean up undesirable gases within the tube. The restricted size of area between the two parts of

anode 14 insures that the gettering and activating material from the capsule 17' will be deposited only on the central portion of the cathode rod 12, and on only an adjacent portion of the interior wall of the envelope 10. None of the activating material will be deposited on the insulating spacers 22 and 24, thus preserving a high insulation value between the cathode and the anode.

Due to the semi-cylindrical form of the anode 14 with the convex surface facing the cathode 12, the actual discharge region within the tube is restricted to a comparatively narrow zone. Thus, the voltage breakdown characteristics of the tube are maintained more nearly uniform than has been the case in previously known tubes of which I am aware.

In order to help initiate the discharge and decrease ionization time, without affecting the electrode spacing in the discharge region, I provide a small strip of radium impregnated material 30 welded to one of side wings 18 of the anode. I have found that in some tubes actually built and tested, the presence of a radium impregnated strip 30, with about two micrograms of radium in the strip, caused the breakdown voltage within the tube to be stabilized within more narrow limits than previously possible. The time required for ionization and breakdown to take place was found to be maintained within very close limits during the life of the tube. Though some of the tubes actually built and tested used a nickel cathode rod and a barium metal within the getter capsule 17', it is contemplated as being within the scope of the present invention to use a molybdenum rod for the cathode 12 and a barium-telluride mixture within the getter capsule 17'.

While I have shown and particularly described an embodiment of the present invention, it should be clearly understood that my invention is not limited thereto, but that modifications within the scope of the invention may be made.

What is claimed is:

1. A gas discharge tube having, within a hermetically sealed casing, a rod-like cathode, a semi-cylindrical anode having a central aperture therein, the convex surface of said anode facing said cathode, a getter capsule supported in spaced relation with the side of said anode remote from said cathode, said capsule having an aperture therein aligned with the aperture in said anode, and an ancillary strip of metal having ionization producing properties supported on said anode in a region remote from the region of closest approach between said semi-cylindrical anode and said cathode.

2. A gas discharge tube including a hermetically sealed casing containing an ionizable gas, a number of electrodes within said casing, said electrodes including an elongated cathode, a semi-cylindrical anode having a central aperture along one side, the convex surface of said anode facing said cathode, a getter capsule supported in spaced relation with the side of said anode remote from said cathode, said capsule having an aperture therein aligned with the aperture in said anode, said anode having a number of diametrically disposed wing-like extensions thereon, at least one of said wing-like extensions supporting an ionization producing strip of metal.

3. A gas discharge tube having, within a hermetically sealed casing, a rod-like cathode, and a semi-cylindrical anode having a central aperture therein, the convex surface of said anode

5 facing said cathode, a getter capsule supported in spaced relation with the side of said anode remote from said cathode, said capsule having an aperture therein aligned with the aperture in said anode.

4. A gas discharge tube including a hermetically sealed casing containing an ionizable gas, and a number of electrodes within said casing, said electrodes including an elongated cathode, a semi-cylindrical anode having a central aperture along one side, the convex surface of said anode facing said cathode, a getter capsule supported in spaced relation with the side of said anode remote from said cathode, said capsule having an aperture therein aligned with the aperture in said anode.

5. A gas discharge tube including a hermetically sealed casing containing an ionizable gas, and a number of electrodes within said casing, said electrodes including an elongated cathode, and a semi-cylindrical anode having a central aperture along one side, the convex surface of said anode facing said cathode, a getter capsule supported on the side of said anode remote from said cathode and spaced from said aperture, said capsule having an aperture therein aligned with the aperture in said anode, said anode having a number of diametrically disposed wing-like extensions thereon and anode supporting rods secured to the side of said extensions remote from said cathode.

6. A gas discharge tube having, within a hermetically sealed casing, an elongated cathode, and a semi-cylindrical anode having its axis 35 parallel to said cathode, the convex surface of said anode facing said cathode, an electron emissive material on said cathode, and an ancillary strip of metal having ionization producing properties supported on said anode in a region remote from the region of closest approach between said semi-cylindrical anode and said cathode.

7. A gas discharge tube including a hermetically sealed casing containing an ionizable gas, and a number of electrodes within said casing, said electrodes including an elongated cathode, a semi-cylindrical anode having its axis parallel to said cathode, an electron emissive material on said cathode, the convex surface of said anode facing said cathode, said anode having a number of diametrically disposed wing-like extensions thereon and anode supporting rods secured to said extensions.

8. A gas discharge tube including a hermetically sealed casing containing an ionizable gas, and a number of electrodes within said casing, said electrodes including an elongated cathode, a semi-cylindrical anode having its axis parallel to said cathode, an electron emissive material on said cathode, the convex surface of said anode facing said cathode, said anode having a number of diametrically disposed wing-like extensions thereon, at least one of said wing-like extensions supporting an ionization producing strip of metal.
